Primary Examiner—M. N. Pandozzi(74) *Attorney, Agent, or Firm*—Armina E. Matthews; Ingrid N. Hackett; Kim W. Zerby(57) **CLAIM**

The ornamental design for a beverage container, as shown and described.

DESCRIPTION

FIG. 1 is a perspective view of the beverage container, embodying the new design;

FIG. 2 is a side elevational view thereof;

FIG. 3 is a top view thereof; and,

FIG. 4 is a bottom view thereof.

The broken lines shown in the drawings are for illustrative purposes only and form no part of the claimed design.
